DIE CASTING MACHINE

Raymond J. Schultz, Madison, Wis., assignor to
 Madison-Kipp Corporation, Madison, Wis., a
 corporation of Wisconsin

Application July 16, 1941, Serial No. 402,656

5 Claims. (Cl. 22—70)

This invention relates to die casting machines and particularly to machines of the type in which a ported pressure chamber is submerged in the melting pot in a substantially fixed position, the molten metal entering the chamber through the ports and being displaced therefrom into the die by a plunger which closes the ports at the start of its displacement stroke.

In past constructions, the nozzle or discharge end of the pressure chamber has been fixed and the other end, at opposite sides of the plunger chamber, has been supported by laterally extending wings which rest on the margins of the melting pot and are capable of limited sliding motion horizontally, but cannot move vertically. This construction results in occasional fracture of the pressure chamber occurring either when the machine is shut down and as the metal in the pot solidifies, or when solidified metal in the pot is being heated up to melting temperature preparatory to putting the machine into action.

The present invention modifies the construction just described, in such a manner that the wing supports permit limited yielding both up and down against spring resistance of such character and range as to relieve the destructive stresses caused by thermal expansion and contraction, without impairing the alignment of the plunger, or its functional movements. Horizontal stresses are relieved by motion at the nozzle end.

The design of the spring support is such as to give the desired high spring resistance and still withstand the high operating temperatures.

A practical adaptation of the invention to a commercial die casting machine is illustrated in the accompanying drawings, in which:

Fig. 1 is a side elevation of so much of a die casting machine as is necessary to illustrate the invention.

Fig. 2 is a plan view of the parts shown in Fig. 1.

Fig. 3 is an end elevation, looking to the left relatively to Fig. 1.

Fig. 4 is a view partly in vertical section and partly in elevation showing how the nozzle end of the pressure chamber is supported and confined.

Fig. 5 is an elevation of the parts shown in Fig. 4, looking to the right relatively to that figure.

Fig. 6 is a view partly in elevation and partly in section showing the yielding mounting for one of the two wings.

The pedestal 11 supports the die mechanism part of which is illustrated. The only parts hav-

ing any direct relation to the present invention are the die components, generally indicated at 12 and the floating nipple plate 13 carried by bracket 14. The nipple plate has a socket which receives the nipple on the pressure chamber and connects it with the sprue in the die, so that metal displaced from the pressure chamber is directed into the die.

The housing 15 encloses the burner mechanism and carries at its upper end the furnace chamber or muffle 16 in which the melting pot is received. The top of chamber 16 is closed except for a main aperture of ovoid configuration, which is filled by the melting pot 17, and except for the two offtakes 18, 19 which include tubular extensions, as shown.

The melting pot conforms in plan to the contour of the opening in the top of chamber 16, so as to fill the same. The form of the pot, as viewed in elevation is indicated in dotted lines in Figs. 1 and 3. Thus the pot depends into the furnace chamber 16 from a supporting marginal flange 21. This surrounds the pot, except at the end adjacent pedestal 11, and rests on a seat surrounding the pot-opening in the top of chamber 16.

Resting on flange 21 is the base flange 22 of a domed cover casting 23 which overlies somewhat more than half of pot 17. This has lugs 24 to support any suitable mechanism (not shown) used to operate the plunger. This mechanism may be hand or power operated and is not directly involved in the present invention.

The portions 25 of flange 22 (see Figs. 1 and 3) are each thickened and provided with an upstanding boss 26, beneath which the lower face is provided with a rectangular notch 27. The notches 27 are above opposite margins of pot 17 and are aligned with each other, and approximately aligned with the plunger chamber 28 of metal forcing unit 29.

The metal forcing unit 29 comprises a hollow casting having an inclined neck 30 with stiffening web 31, the neck extending (as viewed in Fig. 1) upward and to the left from the bottom of the upright plunger chamber 28 and terminating in a nipple 32 which coacts with plate 13. The plunger chamber is bushed, as indicated at 33, and a discharge passage leads from the bottom of this chamber through the inclined neck 30 to the port in nipple 32.

Wing brackets 34 extend from opposite sides of the unit 29. They are aligned and approximately centered on chamber 28, and terminate in pads 35 which enter and are free in the notches 27.

The brackets 34 are each stiffened by top webs 36 and by two spaced flaring bottom webs 37 which shroud the inlet ports 38 (see Fig. 6) through which molten metal enters the plunger chamber. The level of molten metal in pot 17 is kept near the top of the pot so that the ports 38 are submerged.

The bottom of plunger 39 rises on its up-stroke far enough to clear ports 38, and on its down-stroke first closes the ports and then displaces 10 metal from the chamber 28 through the nipple 32 as is usual in machines of this type.

As stated the pads 35 are free in notches 27, but the range of motion is not sufficient to impair the alinement of the plunger. Shouldered studs 41 are threaded into the tops of pads 35 and are closely guided in vertical ways drilled through the bosses 26. Fixed to the upper end of studs 41 are heavy spring elements 42 whose form is clearly shown in the drawings, see particularly 20 Figs. 3 and 6.

These spring elements comprise a central hub 43 in which the upper end of stud 41 is fixed by a nut and two looped spring ends which seat on portions 25 of flange 22 and are fixedly held thereto by nuts on the studs 44. The studs 44 pass through the ends of the springs 42, the thickened portion 25 of flange 22 and through flange 21. They are threaded into the top of housing 16. Machine screws 45 further connect flanges 22 and 21 to the top of chamber 16.

In this way a rigid support is provided for the plunger actuating mechanism, but the chambered end of the metal forcing unit 29 is permitted very limited vertical motion up and down from its normal neutral position against heavy resistance offered by the springs 42. Additional frictional resistance may be imposed by setting up the thrust screws 46. These are provided with check nuts to preserve their adjustment.

The neck portion of the unit 29 is sustained immediately behind nozzle 32 in an orifice formed partly in the pot 17 and partly in the dome 23 (see Figs. 4 and 5). The nozzle has an arcuate boss or rib 47 which seals with the pot 17. A set screw 48 threaded in a boss formed in the dome 23 exerts the desired sealing pressure. The screw 48 is locked by a check nut.

The construction is such that the plunger and plunger chamber are held in alinement, but limited vertical motion of the chamber is permitted adjacent the plunger. However, the springs are so stiff that they do not yield appreciably to the stresses imposed by the plunger. Horizontal creep is permitted adjacent the nipple. Thus shrink strains are relieved and fracture of the unit thereby is avoided, during both heating and cooling of the melting pot.

While some details of the die casting machine have been described to indicate the environment in which the invention develops its utility, the form of the machine is obviously subject to wide variation. The details of mounting the pressure unit in any appropriate die casting machine are the real subject of invention and they too are subject to modification within the scope of the claims which alone define the scope of the invention.

What is claimed is:

1. The combination of a plunger; a pressure unit adapted to be submerged in molten metal and comprising a transverse pressure chamber adapted to receive said plunger and a longitudinal nipple in communication with and remote from said chamber; and a three point support for said unit, comprising means embracing said nipple and permitting longitudinal motion thereof as an incident to thermal expansion and contraction, two guides adjacent, and parallel with the axis of, said chamber and engaged by portions of said unit, and yielding means serving to center said unit in said guides, the yielding means being of sufficient strength to resist the reaction of the plunger, and capable of yielding to relieve shrinkage strains.

2. The combination defined in claim 1 in which the yielding means comprise heavy arcuate spring loops, and the guides include limit stops which so limit motion of the unit as to prevent substantial misalinement of the plunger and pressure chamber.

3. In a die casting machine, the combination 25 of a melting pot; a metal forcing unit at least partially submerged in molten metal in said pot, said unit having at one end a vertical plunger chamber and at the other end a horizontally extending nipple communicating with said chamber; clamping means embracing said nipple and adapted to permit limited horizontal motion; vertical guides for said unit adjacent said chamber and on opposite sides thereof; and yielding means 30 associated with said guides and adequate to sustain said unit against the stresses occasioned by normal operation of the machine, but serving to relieve shrinkage strains.

4. In a die casting machine, the combination 35 of a melting pot; a metal forcing unit at least partially submerged in molten metal in said pot, said unit having at one end a vertical plunger chamber and at the other end a horizontally extending nipple communicating with said chamber; clamping means embracing said nipple and adapted to permit limited horizontal motion; vertical guides for said unit adjacent said chamber and on opposite sides thereof; yielding means 40 associated with said guides and adequate to sustain said unit against the stresses occasioned by normal operation of the machine, but serving to relieve shrinkage strains; and limit stops associated with said guides.

5. In a die casting machine, the combination 45 of a melting pot; a metal forcing unit at least partially submerged in molten metal in said pot, said unit having at one end a transverse plunger chamber and at the other a nipple communicating with said chamber and extending substantially at right angles to the axis thereof; supporting means adjacent said chamber for guiding said unit in limited motion in a direction parallel with the axis of said chamber; yielding sustaining means associated with said guiding means; and means for clamping said nipple 50 while permitting limited motion in the direction of the axis thereof.
